2 SHEETS—SHEET 2.

UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SAFETY PANEL-BOX.

1,324,555.

Specification of Letters Patent.

Patented Dec. 9, 1919.

Application filed September 6, 1918. Serial No. 252,878.

To all whom it may concern:

Be it known that I, HUBERT F. KRANTZ, residing at Brooklyn, in the county of Kings and State of New York, have invented certain new and useful Improvements in Safety Panel-Boxes, of which the following is a specification.

This invention relates to a safety panel box. It comprises certain modifications and improvements over the structures shown and described in my Reissue Patent 14,498 and in my Patent Number 1,292,808, dated Jan. 28, 1919.

A particular object of the present invention is to provide an improved structure in which the front wall of the box may be more readily assembled and disassembled with the remainder of the box when occasion requires.

20 A further object is to provide improved contact supporting means of a character to reinforce and stiffen the box, the reinforcing and stiffening effect being particularly serviceable in retaining certain screw retaining apertures in alinement to thereby facilitate easy attachment of the removable top wall.

Other objects and aims of the invention, more or less specific than those referred to above, will be in part obvious and in part pointed out in the course of the following description of the elements, combinations, arrangements of parts and applications of principles, constituting the invention; and 35 the scope of protection contemplated will be indicated in the appended claims.

In the accompanying drawings which are to be taken as a part of this specification, and in which I have shown merely a preferred form of embodiment of the invention:

Figure 1 is a longitudinal sectional view through a panel box constructed in accordance with this invention.

45 Fig. 2 is a transverse sectional view taken substantially upon the plane of line II of Fig. 1, and

Fig. 3 is a top plan view of the box shown in Fig. 1, parts being broken away to better disclose the construction.

Referring to the drawings for describing

in detail the structure which is illustrated therein, the reference character L indicates the panel box generally. This may be made of any suitable material, but is preferably made of sheet metal. The bottom wall 1 and opposite side walls 2 and 3 are made of a single piece of sheet metal bent into U-cross section. The end walls 4 and 5 are separately formed and are provided with marginal flanges 6 at each of their four edges, said flanges being disposed to telescope inwardly between the adjacent end portions of the walls 1, 2 and 3. Suitable rivets or the like, as 7, are employed for connecting the end wall sections in position. The top wall is made up of two sections, one, which may be referred to as the main section, is indicated by the reference numeral 8, and the other, which may be referred to as the hinged section or door, is indicated by the reference numeral 9. The sections 8 and 9 are connected together by a hinge 10 extending transversely across the box and each of the sections are provided with marginal flanges 11 which telescope downwardly over the side and end walls.

The top wall may be held in position by any suitable means but is preferably held by a plurality of screws. One, or more of these, 80 as 12, extends through apertures, as 13, formed in the main section and engage within threaded apertures 14 formed in the top flange, as 15, of the end wall 4. The other two, as 16 and 17, extend through the 85 apertures 18 formed through the main section and engage within threaded apertures 19 which are provided in bracket pieces 20 fixed to the side walls 2 and 3 at points near the hinge 10.

The hinged section 9 is held in position by the hinge 10 and by a latch 21 which is connected to be operated by a handle 22 to swing into and out of position beneath a top flange 23 of the end wall 5, said flange constituting an overhanging ledge for the purpose of receiving the latch 21 beneath it.

The switch mechanism, as G, is arranged within the box, being preferably fixed to the main section 8 and having a handle 24 100 projecting through an opening 25 formed through said section 8.

The switch mechanism is substantially the same as that illustrated in the above mentioned patent and copending application, and as more fully shown and described in my 5 Patent Number 1,292,805, dated Jan. 28, 1919. It comprises a swinging double ended blade 27 adapted to be swung by the handle 24 for moving its opposite ends into and out of electrical engagement with the main line contacts 28 and the branch line contacts 29.

A toggle 30 is interposed between the handle and the blade adapted to hold the blade "on" when the toggle is made and to permit the blade to move "off" under the impulse of 15 a suitable spring, as 31, when the toggle is broken.

The branch line contacts are mounted upon an insulating base 32 which is fixed to the bottom wall 1 of the box and which also 20 carries suitable fuse clips 33 for supporting fuses 34 in association with the branch line contacts and in a position of accessibility when the hinged section 9 of the front wall is swung open.

25 The main line contacts 28 are carried upon the under surface of an insulating block 35 which is in turn supported by a bridge piece H which extends between the side walls 2 near the upper edge of said side walls. The 30 bridge piece H is preferably of sheet metal and is provided with end flanges 36 lying flat against the inner surface of the side walls and rigidly connected thereto by suitable rivets or the like, as 37.

35 The insulating block 35 may be connected to the bridge piece in any suitable manner and serves as stiffening means for the intermediate portion of the bridge piece. The bridge piece thus constitutes a rigid and efficient brace and reinforcement for the side walls capable of holding them in a fixed and predetermined position relative to each other so that the screw receiving apertures 18 and 40 19 of the top wall and of the brackets 20 properly mate with each other at all times. The bridge piece prevents any bowing or bending of the upper edge portion of the side walls out of proper relation to each other, which bowing or bending might be 45 occasioned by inaccuracy of manufacture or by rough handling. In this connection it should be noted that during manufacture, while the apertures 18 in the main section 8 may, of course, readily be spaced a fixed 50 distance from each other, yet the apertures 19 which must mate with the apertures 18 may, or may not be in a pre-determined position according to whether or not the side walls stand true and accurate. One of the 55 side walls may be bent inwardly to a slightly greater extent than the other. This would prevent proper mating of the apertures. The bridge piece H, for carrying the main line contacts, however, is of a fixed length

and when fixed between the side walls it 65 positively spaces the apertures 19 so that they correctly mate with the apertures 18.

The use of the bridge piece, as a means to support the main line contacts, is very effective since the bridge piece not only conveniently supports said contacts in a proper position for co-operation with the switch blade but it also, together with the insulating block 35, constitutes a guard member over said contacts after the front wall has 70 been removed. Accidental engagement of an operator's hand, after the front wall has been removed, with the live main line contacts, is thus to a large extent prevented.

In order to increase the safety afforded by 80 the bridge piece to the main line contacts, said contacts preferably have their outer end portions, as 42, bent downwardly so as to support the wire terminals 43 in a more protected position.

85 A plunger 38 is formed as a part of the switch mechanism, being preferably connected to the heel of the toggle as at 39 so that when the toggle moves "on" the plunger is projected outwardly, while when the toggle moves "off" the plunger is withdrawn. This plunger cooperates with a link 40 which is connected with the latch 21 for operating said latch from the switch mechanism in the same manner as fully shown and described in 90 connection with my patent and application above referred to, namely, to cause the latch to stand in latching position whenever the switch is "on" and to cause "off" movement of the switch whenever the latch is unlatched.

95 A semi-circular retaining disk 41 is also provided upon the hinged section, or door 9 concentric with the hinge 10 adapted to travel into the path of movement of the plunger 38 when the door is opened, thus to prevent "on" movement of the switch while the door is opened, in the same manner as shown and described in my pending application Serial No. 158,957 above referred to.

100 It will be seen that since the main line contacts 28 are in a fixed position in front of the blades 27, said blades and contacts, when the switch is "on", co-operate to prevent detachment of the front wall even after the 105 screws 12 and 16 have been removed.

110 It should be also pointed out that the flanges 11 upon the two sections of the front wall serve to prevent any shifting of the front wall with respect to the remainder of the box such as might enable the switch blades or the latch 21 to release their hold, and permit the front wall to be removed. The flanges 11 also serve to close any crack which might otherwise occur between the 115 top wall and the adjacent side walls due to looseness of any of the parts.

120 As many changes could be made in this

construction without departing from the scope of the invention as defined in the following claims, it is intended that all matter contained in the above description or 5 shown in the accompanying drawings, shall be interpreted as illustrative only and not in a limiting sense.

Having thus described my invention, what I claim as new and desire to secure by Letters 10 Patent is:—

1. A device of the class described comprising a box having opposite side and end walls and having a removable front wall, removable retaining means interengaging 15 between the front wall and the opposite side walls to retain the front wall in position, stiffening means for said side walls extending therebetween adjacent said retaining means for the purpose described, and said 20 stiffening means being of a character to support switch contacts and to serve for protecting said switch contacts when the front wall is removed.

2. A panel box having opposite side walls 25 spaced apart, a brace extending between said side walls to retain said side walls in fixed relation to each other, switch mechanism within the box movable into "on" and "off" positions, a contact with which said switch 30 mechanism coöperates, and said contact being carried and supported by said brace.

3. A panel box comprising opposite side walls spaced apart, a front wall, retaining means for the front wall interengaging between the front wall and said opposite side walls, switch mechanism within the box, a contact within the box for coöperating with the switch mechanism, and supporting means for said contact of a character to hold 40 said side walls in position to facilitate application of said front wall retaining means.

4. A panel box comprising opposite side walls spaced apart, a front wall, switch mechanism within the box, the front wall 45 having apertures formed therethrough and the side walls having parts providing apertures intended to mate the apertures of the front wall whereby to receive retaining means for the front wall through said mating apertures, switch mechanism within the box, a contact with which the switch mechanism coöperates, and a support for said contact comprising means to retain the side walls in position with said apertures mating.

5. A panel box comprising a piece of sheet material bent into U cross section to provide a bottom wall and opposite side walls, a separately formed front wall adapted to be connected to said side walls, said front wall and 50 side walls providing parts having apertures intended to mate with each other for receiving the front wall retaining means therethrough, switch mechanism within the box, a contact with which the switch mechanism

coöperates, and a support for said contact 65 comprising means extending between and connected to the side walls near their upper edges whereby to hold said side walls in position with the apertures thereof adapted to mate the apertures of the front wall. 70

6. A device of the class described comprising a box having a removable wall, a switch mechanism within the box, a contact also within the box with which the switch mechanism is adapted to coöperate, and a 75 support for said contact fixed within the box in a position intermediate said contact and said removable wall so as to serve as guard means for the contact when said removable wall is removed. 80

7. A device of the class described comprising a box having a removable wall, a switch mechanism within the box, a contact also within the box with which the switch mechanism is adapted to coöperate, a support for said contact disposed to serve as guard means for the contact when said removable wall is removed, the box having also opposite side walls, said support including a bridge piece extending between and reinforcing said side walls relative to each other, and an insulating block with which the contact is directly connected, said insulating block being fixed to and reinforcing the bridge piece. 90

8. In a device of the class described, a switch device including a switch blade element, an operating element for the switch blade element and a contact element with which the switch blade element coöperates, 100 a box for said elements, said box having opposite side walls spaced apart, and a brace extending between said side walls to reinforce said side walls and serving as a supporting means for at least one of said switch 105 device elements.

9. In a device of the class described, a switch device including a switch blade element, an operating element for the switch blade element and a contact element with 110 which the switch blade element coöperates, a box for said elements, said box having opposite side walls spaced apart, a brace extending between said side walls to reinforce said side walls and serving as a supporting means for at least one of said switch device elements, said box also having a removable front wall, and said brace being mounted independently of said front wall so as to support the mentioned switch device element irrespective of the removal of said front wall. 115

10. A device of the class described comprising a box having a removable wall, a switch device within the box made up of a 120 switch blade element, an operating element for the switch blade element and a contact element with which the switch blade ele-

ment coöperates, and a support for one of said switch device elements fixed within the box in a position intermediate said mentioned element and said removable wall so as to serve as guard means for said mentioned element when said removable wall is removed.

In testimony whereof I affix my signature in the presence of two witnesses.
